LEADER HOLDER

Albert G. Lampe, Madison, Wis., assignor of
forty-nine per cent to Gordon Engineering,
Inc., Madison, Wis., a corporation of Wisconsin

Application December 12, 1949, Serial No. 132,537

4 Claims. (Cl. 242—96)

1

This invention relates to a device for removably retaining leaders, gut, plastic, wire or similar short lengths of tackle which will be held securely in place while in a fishing kit.

An important object of this invention is to provide a leader holder which is relatively simple in design and construction, cheap to manufacture in large quantities, easy to assemble for use, light in weight, and very efficient for its intended purpose.

A further object of this invention is to provide a device of the character described which is also adapted to securely and removably retain swivels, hooks, and similar objects in addition to leaders.

A further object of this invention is to provide a leader holder comprising a pair of cups each having a cylindrical body portion and a flange, means for resiliently retaining the body portions together, a sleeve embracing said assembled body portions and received between said flanges, resilient holding rings, and means for securely retaining said rings on said sleeve.

These, together with various ancillary objects and features of the invention which will later become apparent as the following description proceeds, are attained by the device, a preferred embodiment of which has been illustrated, by way of example only, in the accompanying drawings, wherein:

Figure 1 is an end elevational view of the device;

Figure 2 is a side elevational view of the device;

Figure 3 is a sectional view taken substantially on the plane of section line 3—3 of Figure 1;

Figure 4 is a group view in perspective of the cup members; and

Figure 5 is a perspective view of the sleeve with one of the resilient holding rings mounted thereon.

Specific reference will now be made to the drawings. In the several views, in the accompanying drawings and in the following specification, similar reference characters indicate corresponding elements throughout.

The holder of the instant invention is indicated generally at 10 and includes a pair of cup members having substantially cylindrical body portions 12 and 14 and enlarged flanges 16 and 18, respectively, the free edges of the flanges including annular turned lips 20 and 22 for a purpose to be described hereinafter. The bases of the body portions 12 and 14 are provided with central apertures 24 through which extend a headed socket member 26 which is internally threaded to receive a headed screw

2

23, as will be readily apparent from Figure 3. A coil spring 30 is wound about the socket member 26 and interposed between the head thereof and the base of the body portion 14, the spring being so tensioned as to normally urge the cups together or into a closed position. Thus, it will be seen that the distance between the assembled cups may be adjustably varied and resiliently retained in this adjusted position by merely turning the headed screw 28.

Embracing the body portions 12 and 14 when they are in an assembled position is a sleeve 32 which is positioned between the cup flanges 16 and 18. A plurality of resilient holding members 34 are retained on the sleeve 32 between the flanges 16 and 18, each of the holding members being a rubber ring having an enlarged annular portion 36 at one end, a flange 38 at its other end and a reduced shank portion 40 between these ends. The rings are so positioned on the holder that the flanges 38 abut the sleeve 32 and the enlarged portions 36 of the rings press against or abut each other, as at 42, to provide a plurality of annular spaces 44 for resiliently and removably retaining the leaders and other fishing tackle of relatively short length. The inturned annular lips 20 and 22 on the flanges 16 and 18 of the cups serve to press against the enlarged portions 36 of the outermost rubber rings 34, that is, the rings adjacent the flanges 16 and 18, to hold the rings in an assembled position on the holder, as will be readily understood with reference to Figure 3.

In use, the holder is assembled in a manner which will be readily obvious to those skilled in the art. The annular spaces 44 between the resilient or rubber rings 34 serve to securely and removably hold leaders, gut, plastic, wire, or similar short lengths of tackle. The annular spaces 44 can also retain somewhat larger equipment, such as swivels and hooks, which will cause adjacent rings to separate, which action will, in turn, compress the spring 30 on the socket member 26 to take up this expansion. The sleeve 32 serves to prevent the central rubber rings from falling within the space between the bases of the body portions 12 and 14 of the cups. It is understood that the entire holder may be fabricated of suitable light-weight metals, such as aluminum, and of light-weight plastics. While it is preferred that the resilient rings 34, 36, 38, 40 be made in sections so that the capacity of the holder may be varied, using a correspondingly larger sleeve 55 32, it is to be understood that the resilient rings

34, 36, 38, 40 may be molded as an integral unitary part.

In view of the foregoing description taken in conjunction with the accompanying drawings, it is believed that a clear understanding of the device will be quite apparent to those skilled in this art. A more detailed description is accordingly deemed unnecessary.

It is to be understood, however, that even though there is herein shown and described a preferred embodiment of the invention, the same is susceptible to certain changes fully comprehended by the spirit of the invention as herein described and within the scope of the appended claims.

Having described the invention, what is claimed as new is:

1. A leader holder comprising a pair of cups each having a cylindrical body portion and a flange, means for resiliently retaining the body portions together, a sleeve embracing said assembled body portions and received between said flanges, resilient holding rings encompassing said

sleeve, and means for securely retaining said rings on said sleeve.

2. The combination of claim 1 wherein said rings are made of rubber each including an enlarged peripheral portion, a flange abutting said sleeve, and a reduced shank portion interconnecting said enlarged portion and said flange, the enlarged portions of said rings abutting each other and cooperating with said shanks and flanges to form annular spaces for removably receiving leaders and similar fishing tackle.

3. The combination of claim 2 wherein said means for retaining said rings on said sleeve includes inturned lips at the free edges of said cup flanges engaging the enlarged portions of the outermost rings adjacent said cup flanges.

4. The combination of claim 1 wherein said means for resiliently retaining the body portions together includes a spring-urged screw extending through the body portions of said cups.
